TRANSIT CONCRETE MIXER

Hugh P. Paris, Seattle, Wash., assignor, by mesne assignments, to Paris Transit Mixer Co., Seattle, Wash., a corporation of Washington

Application November 13, 1928, Serial No. 319,067

3 Claims. (Cl. 83—73)

This invention relates to concrete mixers, more particularly of the transit type, and aims primarily to provide a concrete mixer wherein the aggregates are intimately intermixed by slump action both laterally and longitudinally whereby a uniform mix is obtained and the resultant product has a high breaking strength.

Contemplated by the present invention is a concrete mixer embodying a supporting frame; a volatile wobbling mixing shell cradled upon said frame; means for driving said shell; means for charging said shell; means for dumping the mix; and water supply means for the aggregates, all of which are important objects of the invention and are to be correlated in the broad aim of enhancing the efficiency of the mixer for general use.

The above, and additional objects which will hereinafter be more specifically treated, are attained by such means as are shown in the accompanying drawings, described in the following specification and then more clearly pointed out in the claims, which are appended hereto, and form a part of this application.

With reference to the drawings in which there are illustrated several embodiments of the invention, and throughout the several views of which like characters of reference designate similar parts.

Figure 1 is a side elevation of a transit concrete mixer comprehended by the present invention.

Fig. 2 is an end elevation of the same, certain parts being in section and certain other parts broken away for clarity of illustration.

Fig. 3 is a fragmentary plan view thereof.

Fig. 4 is a diagrammatic transverse view of the mixing shell illustrating the manner of reinforcing same.

Fig. 5 is a plan view of a slightly modified type of transit mixer.

Fig. 6 is a vertical transverse section taken through 6—6 of Fig. 5.

Fig. 7 is a side elevation thereof.

Fig. 8 is a diagrammatic end view of the same in dumping position.

Fig. 9 is a side elevation of another modified type of transit mixer.

Fig. 10 is a rear end elevation of the same.

Fig. 11 is an enlarged fragmentary plan view of the driving mechanism for the mixing shell thereof, certain parts being in section, and

Fig. 12 is an enlarged fragmentary end elevation of such mechanism, certain parts being

broken away and certain other parts being shown in section.

Before taking up the detailed description of the drawings, a general exposition of the specific purposes, features, and functions of the transit concrete mixer evolved by the present invention will be undertaken. Heretofore, considerable difficulty has been experienced in keeping the interior of concrete mixer shells clear of hardened concrete, due primarily to the numerous baffle plates commonly employed and required in such shells to distribute and mix the aggregate, which baffle plates also function to retard and impede dumping of the mixed aggregates. Further objections and disadvantages of the transit mixture heretofore in use are: the length of their mixing shells and their mode of construction, which entailed and necessitated the employment of trucks having excessively long wheel bases; rendered the charging of such mixing shells extremely difficult; permitted utilization of approximately only one-third of the volumetric capacity of the mixing shells; precluded proper and efficient distribution of water to the aggregates; lacked adaptability or capability for mixing stiff or relatively dry concrete due to the fact that the same becomes tacky and lumpy and adheres to the interior baffles or blades of the mixing shells thus effectively preventing clean dumping of the mixed aggregates; and the fact that the maximum charges of said mixing shells are too small for all practical and profitable purposes. Therefore, a primary object of this invention is to obviate the objections and disadvantages of the transit mixers now in general use. Another primary object is the provision of a transit mixer of novel shape and construction, wherein no baffle plates, blades or other interior obstructions of any kind are employed, which fact permits and insures of a clean and complete discharge of the mixed aggregates and precludes possibility or probability of any corrosion occurring within the mixing shell. Another primary object is the provision of a compact and relatively light transit mixer which may be mounted upon a truck having a relatively short wheel base thus materially increasing the maneuvering range and effectiveness of the unit. Another primary object is the provision of a transit mixer which may be rapidly and readily charged with aggregates and wherefrom the mixed aggregates are expeditiously and readily dumped without the use of complicated and costly hoisting devices. Another primary object is to provide a transit mixer wherein approximately two-thirds of the volu-

metric capacity of its mixing shell is effectively utilized during mixing of the aggregates, thus materially increasing the size of the charges in each and every instance and in consequence 5 thereof the earning capacity of the unit. Another primary object is the provision of a transit mixer especially designed and readily adaptable for mixing relatively dry aggregates and for completely and rapidly discharging the same when 10 mixed. Another primary object is the provision of a transit mixer wherein the water is properly and uniformly distributed or sprayed upon the aggregates. Another primary object is the provision of a transit mixer wherein the aggregates due to the shape of the mixing shell and 15 its rotating and wobbling movements are intimately intermixed in a manner which approximates very closely the mixing of aggregates by the shovel method.

20 Beginning the more detailed description by reference to the accompanying drawings, the numeral 11 designates a transversely disposed mixing shell or chamber, which is polygonal in cross-section, and which for purposes of the 25 present disclosure is preferably illustrated and hereinafter described as being of hexagonal formation. The shell 11 is closed at its ends and to provide for charging of the same with aggregates 30 and for the discharging or dumping the mix I prefer to utilize one of the sides of such shell as a door 12, which is hinged as at 13 and when closed is secured by latches 14. A small gate 16 slidably disposed in guides 17 is mounted upon the door 12 to permit of the discharge of relatively small 35 quantities of the mixed aggregates, as is often found desirable.

Rigidly secured and eccentrically mounted upon the ends of the mixing shell 11 are annular journals or raceways 19 and 20, respectively, to 40 which are similarly secured annular sprocket wheels 21 and 22, respectively, it being here noted that the axis of the annular journal 19 is disposed below the axis of the mixing shell, while the axis of the annular journal 20 is disposed 45 above the axis of the mixing shell for a purpose hereinafter set forth. The journals with their correlated sprockets are also disposed in spaced relation to their respective ends of the shell 11 by a series of spacers or bosses 24, which are of 50 different lengths, so that such journals and their sprockets are maintained in parallel relation with respect to each other and in perpendicular relation to the axis of rotation of the shell 11. The journals 19 and 20 are cradled or 55 supported for rotation upon rollers 26 mounted upon a supplemental frame 27, which is provided with a series of rollers 29 operating in channel guides 30 secured to a truck frame 32. Rigidly secured to one side of the supplemental frame 27 60 is a rack 33, with which meshes a pinion 34 journaled upon the truck frame 32 for rotation by a crank handle 35. Obviously, when the crank 35 is turned in a clockwise direction the supplemental frame 27 is moved rearwardly upon the truck frame 32, to the dumping position indicated in dotted lines in Fig. 1, and to limit the rearward movement of the supplemental frame I provide a stop member 31, which is rigidly secured to the side of the truck frame 32 adjacent its rear end, for abutment with the rear end of the rack 33. A spring-pressed pawl or dog 38 is adapted to 65 normally engage the rack 33 when the supplemental frame 27 is in its forward or advanced position or at any intermediate point between a fully advanced or fully retracted position, as

will be manifest and apparent by referring to Fig. 1, so that the supplemental frame 27 may be locked to the truck frame 32 during mixing operations, or if for any reason may be locked to the latter in any intermediate position between the mixing position and dumping position.

The sprocket wheels 21 and 22 are connected by sprocket chains 40 to sprocket pinions 41, which latter may be driven in any convenient manner. In the present instance, however, I have shown a shaft 43 adapted to be optionally engaged with a driving shaft 44 of any standard type of power take-off. A bevel pinion 45 and a bevel gear 46 transfer the power from the shaft 43 to differential gearing 48, which in turn imparts power to jack-shafts 50 and 51, to the outer ends of which are rigidly secured the sprocket pinions 41. By interposing the differential gearing 48 between the sprocket pinions 41 and the shaft 43, it will be evident that a uniform amount of power will be applied or transmitted to each of the sprocket chains 40, thus making for equal wear on all parts. All of the aforementioned mechanism, with the exception of the driving shaft 44, is operatively mounted upon a transversely disposed frame 52 rigidly secured to the forward end of the supplemental frame 27, substantially in the manner illustrated in Figs. 1 and 3.

A band brake 53, of any standard type, mounted upon the jack-shaft 50 and attached as at 54, in any well known manner to the frame 52, is provided for the purpose of positively holding the mixing shell 11 in position during dumping operations.

Longitudinally disposed water storage tanks 55 are mounted upon the supplemental frame 27 in spaced relation to the ends of the mixing shell 11, as shown more clearly in Fig. 2, said tanks 55 being interconnected by a common discharge 40 pipe or conduit 56, which extends longitudinally through the mixing shell 11 and is provided with a series of aligned apertures 57 spaced at intervals throughout its length. Mounted for oscillative movement upon the discharge pipe 56 is 45 an oscillative sleeve or valve pipe 58 having a series of aligned apertures 59, which register upon occasion with the apertures 57 of the pipe 56. It will be noted by referring to Fig. 2 that the axes of the pipes 56 and 58 are co-extensive 50 with the axis of rotation of the mixing shell 11 and in consequence thereof, such pipes are not affected by the rotation of said shell.

To reinforce the interior of the mixing shell 11 I have found it desirable in some instances 55 to provide a series of tie rods 61, which are rigidly secured at their terminals to the opposing flat sides of the said shell, or to one flat side and the opposing angles of the same, substantially in the manner indicated diagrammatically 60 in Fig. 4. These rods are disposed or distributed in staggered relation throughout the length of the mixing shell and function to stiffen the flat sides thereof and break up any lumps of dry aggregates that tend to float in the mix.

Where it is necessary to transport and mix a large quantity of aggregates I have found it desirable and essential to slightly modify the mixer, substantially in the manner illustrated in Figs. 5 to 8, inclusive. In this type the mixing shell 11a having a side door 12a at one end thereof is longitudinally disposed upon its correlated truck, thus making it possible to have a mixing shell of considerable length and capacity. This form of construction requires a tilting 75

means, consequently, the mixing shell with its correlated parts may be cradled upon a laterally tilting supplemental frame 70 pivotally connected, as by a shaft 71, see Figs. 5 and 6, to an intermediate frame 73 longitudinally disposed upon and rigidly secured to the truck frame 32, or upon a similarly tilting supplemental frame 70a pivotally connected, as by pins 71a, see Fig. 7, to an intermediate frame 73a longitudinally disposed upon and rigidly secured to the truck frame 32. In this connection it is to be noted that the supplemental frame 70 is superimposed upon the intermediate frame 73, as shown in Fig. 6, while the supplemental frame 70a is disposed in the same horizontal plane with the intermediate frame 73a, as is shown in Fig. 7, depending upon the individual or particular design of its correlated truck chassis. While any convenient hoisting means may be employed to effect lateral tilting of the supplemental frames 70 or 70a, actual experience has demonstrated that a multiple lift hydraulic jack 74 manually operable by an actuating handle 75 to be very efficient and reliable for this purpose, the base of said jack being pivotally secured to the truck frame 32, while the upper lift member of the jack is pivotally connected and secured to the supplemental frame 70 or 70a, as indicated at 76 in Fig. 6 or at 76a in Fig. 8.

When the mixing shell 11a and the supplemental frame 70 are fully elevated or tilted by the jack 74 to the dumping position indicated by the dotted lines in Fig. 6, gravity tends to roll or unseat the shell 11a from its supporting rollers 26a, and in order to effectually and positively prevent unseating of the shell I provide a roller 78 for each end of the latter, which rollers are mounted upon bearings 79 rigidly secured upon the ends of the supplemental frame 70 between the supporting rollers 26a, substantially in the manner illustrated in Fig. 6, and are adapted and designed to engage and roll within the inner surfaces of the annular journals 19a and 20a, so that during tilting movements of the shell 11a and frame 70 by the jack 74, such shell is maintained at all times by the rollers 78 in cradled relation within its correlated supporting rollers 26a, as will be manifest and apparent. The jack 74 also functions as a stop to limit the tilting movement of the frame 70 and thus prevents the weight of the shell and the aggregates from overturning said frame, the supplemental frame 70a is also equipped in a similar manner, as above described for the frame 70, so that when the same is tilted as illustrated in Fig. 8, its correlated mixer 11a will not become unseated.

In both forms of transit mixers, hereinbefore shown and described, it is desirable to control the supply of water to the mixing shells 11 or 11a from the driver's seat, and in the transversely disposed type of mixing shell shown in Figs. 1 to 3, inclusive, the numeral 80 designates a control rod, which extends rearwardly from the operator's cab, not shown, and at its rear end is connected to one arm of a bell crank lever 81 pivotally mounted upon the truck frame 32, the other arm of which engages or abuts the lower end of a push rod 82 pivotally connected at its opposite or upper end to an oscillative arm 83 rigidly secured to one end of the oscillative sleeve or valve pipe 58, whereby a pull upon the control rod 80 exerts an upward thrust upon the push rod 82 and its correlated arm 83, causing circumferential movement of the sleeve 58 upon the pipe 56, so that the apertures 59 are brought into

registration with the apertures 57 to spray the aggregates with the necessary quantity of water during mixing operations. Upon retraction of the control rod 80 a tension spring 84 connected at one end to the periphery of the sleeve 58 and at its other end to the water tank 55 serves and functions thereto to effect reverse circumferential movement of the sleeve 58 and thus move the apertures 59 out of registration with the apertures 57, thereby shutting off the water. When the supplemental frame 27 is moved rearwardly to dump the load the lower end of the push rod 82 slides off the bell crank 81, but upon return of the frame 27 to a normal or mixing position the push rod 82 is again brought into engagement or abutment with the bell crank 81 it will therefore be apparent that by fabricating these parts in the manner herein shown and described, that such construction readily permits of independent movement of the supplemental frame 27 and its correlated parts relative to the control rod 80 and its bell crank 81.

In the longitudinally disposed type of transit mixer disclosed in Fig. 7 a cable 85 extends rearwardly from the operator's cab, not shown, through the pivot pins 71a around suitably disposed pulleys 85' and thence upwardly therefrom to the operating handle of a water control valve 86 connected to the outlet of a water storage tank 55a. A tension spring 87 functions to normally close the valve 86 and retract the cable 85.

In some instances and under certain conditions it is desirable to dump the mixed aggregates at some distance from the truck, and for this purpose I employ a chute 90 illustrated in Figs. 7 and 8, which chute may be effectively employed with either the end or side dumping type of mixer. The chute 90 is fabricated in any desired length and at its upper or inner end has a width equal to the door 12a, wherefrom it converges outwardly and downwardly in the manner shown in Fig. 7, said chute being preferably supported or suspended by rapidly and readily detachable means, such as chains 91, to a bar or rod 92 mounted for pivotal movement, at a point substantially midway its length, upon a pin 93 secured to a longitudinally disposed member 94 fixedly mounted upon one side of the supplemental frame 70. This method of mounting the chute 90 permits turning the same in any direction to thereby facilitate and expedite dumping of the concrete in the desired location.

In operation a transit mixer of either the end or side dump type, hereinbefore described, is positioned under a batching chute with its door 12 or 12a open and uppermost, this permits of rapid and ready charging of the mixing shell 11 or 11a with the desired quantity and proportion of aggregates, following which the door 12 or 12a is closed and clamped. The water storage tanks 55 or 55a are then filled and the transit mixer started for its destination. At a proper distance from its point of delivery the shafts 43 and 44 are interconnected by the clutch mechanism disclosed in Fig. 3, or by any other convenient and suitable means, to thereby impart rotative and wobbling movement to the mixing shell 11 or 11a and the necessary quantity of water is sprayed upon the aggregates. As the mixing shell 11 or 11a rotates and wobbles the flat sides of the same function due to rotative movement to carry the aggregates on the bottom upwardly and dump or slump such aggregates upon and into the upper aggregates, and coincidentally and concurrently therewith the endwise wobbling move-

ment of such shell produced by the eccentrically mounted journals 19 and 20 in one type, or 19a and 20a in the other type having their axes disposed upon opposite sides of the axis of their correlated shell as hereinbefore set forth, which in combination with the rotative movement of the particular shell causes slumping of the aggregates from the ends of such shell to the center of same, whereby the entire charge of aggregates 10 in the shell 11 or 11a are thoroughly and intimately intermixed. Obviously, therefore, the combined rotative and wobbling movements of the shell 11 or 11a produces a thorough intermixture of the aggregates both in lateral and 15 longitudinal directions.

In the end dump type of transit mixer, when it is desired to dump the mix, the rotating mixing shell 11 is stopped with the door 12 in the dumping position, substantially as indicated in Fig. 1, 20 by applying the brake 53 which also functions to positively hold the shell in such position during dumping, whereupon the shafts 43 and 44 are disconnected, the movable supplemental frame 27 carrying the mixing shell and correlated parts is 25 then moved rearwardly, from the full line position to the dotted line position shown in Fig. 1 by the operator turning the crank 35, following which latches 14 are released allowing the mixed aggregates to fall out. Manifestly, by utilizing 30 one entire side of the shell 11 for a door and by disposing the lower flat side at the angle shown in Fig. 1 a complete and clean discharge of the entire contents of the mixing shell is effected and secured, and due to the elimination of all baffle 35 plates nothing will stick to the inner surfaces of the shell to cause corrosion. However, if it is desired to discharge only a small amount of the intermixed aggregates, the small or auxiliary door 16 is utilized for this purpose, and being mounted upon the large door 12 will operate from 40 the same dumping position.

Actual experience has shown and demonstrated the advisability and necessity of locating the mixing shell 11 somewhat forwardly of the rear wheels of the truck, during loading and mixing operations, which fact necessitates the rearward movement of such shell for dumping, and in this connection it may be well to state that any tendency for the mixing shell 11 and its correlated movable supplemental frame 27 to overbalance 50 while in a rearward or dumping position is effectually and definitely prevented by the supplemental frame rollers 29 abutting the upper sides of their guide channels 30 rigidly secured to the truck frame 32.

55 In the side dump type of transit mixer, the side door 12a is hinged as at 13a and is secured in a closed position by latches 14a and when it is desired to dump the mix, the mixing shell is stopped and held in the position indicated in full lines in Fig. 7, following which the chute 90 is attached with its inner end disposed contiguous to the door 12a, which is then opened to discharge the major portion of the mixed aggregates into the chute 90, however, to effect complete discharge of the contents of the shell, the jack 74 is actuated to elevate the supplemental frame 70 or 70a with its mixing shell 11a, whereby the slope or angularity of the lowermost flat wall of the shell is increased resulting in the entire 60 evacuation of the latter, as will be manifest and apparent. To facilitate and expedite a complete and clean discharge of the mixing shell 11a, particularly where the door 12a occupies only a portion of one of the flat sides of said shell,

as shown in Fig. 7, I have found it expedient in practice to locate the rear pivot pin 71a adjacent the chute 90 in a plane below that of the forward pivot pin 71a, which form of construction permits of the discharge end of the mixing shell being depressed to a considerably lower point than is possible when both pivot pins are in the same horizontal plane.

In Figs. 9 to 12, inclusive, wherein another modified type of transit mixer is disclosed, the 10 numeral 100 designates a longitudinally disposed mixing shell, hexagonal in cross-section, and especially designed for end dumping, said shell having eccentrically mounted raceways 101 rigidly secured upon the ends thereof for rotation 15 upon rollers 102 mounted upon the ends of a similarly disposed supplemental frame 103, which latter is tiltably mounted at its rear end upon the rear end of a truck chassis 104, whereby the mixing shell 100 and supplemental frame 103 20 may be tilted to the dumping position shown in Fig. 9. Movement into dumping position is effected in any suitable manner, and I have herein shown a cable 105 which may be connected to any suitable vertical hoist, not shown, in a manner common in the dump truck art. The pivot connection between the supplemental frame 103 and truck chassis 104 may be of any type found suitable in the dump truck art, but, in the present instance the frame 103 is provided with depending brackets 106 and the chassis 104 is provided with rearwardly extending brackets 107 having laterally extending gudgeons 108 which are journalled for oscillative movement within the lower ends of the depending brackets 106, as shown 30 more clearly in Figs. 10, 11 and 12, the pivotal mounting herein shown and described is merely illustrative as any pivotal mounting may be employed which is found suitable.

A longitudinally disposed shaft 109 connected 40 at its forward end to any standard type of power take-off, not shown, is journalled at its rear end within an extension 110 of one of the brackets 107, whereat it is interconnected by bevel gearing 111 to a laterally disposed shaft 112 journalled for rotation at its inner end within the extension 110 and at its outer end is journalled within and extends through the adjacent bracket 107 and gudgeon 108. Fixedly secured to the outer terminal of the shaft 112 is a sprocket wheel 113 45 connected by a sprocket chain 114 to a sprocket wheel 115 having a bevel pinion 116 formed integral therewith, or otherwise rigidly secured thereto, said sprocket wheel 115 and bevel pinion 116 being fixedly secured to a stub shaft 117 journalled for rotation within an extension 118 of the adjacent bracket 107.

55 Meshing with the bevel pinion 116 is a bevel gear 119 which is fixedly secured upon the rear terminal of a shaft 120 longitudinally disposed upon one side of the supplemental frame 103 and journalled for rotation adjacent its ends within brackets 121 fixedly secured to the side of said frame aforementioned.

Fixedly secured to the shaft 120 contiguous to the brackets 121 are sprocket pinions 122 which are connected by sprocket chains 123 to annular sprocket wheels 124 rigidly secured to the raceways 101 of the mixing shell 100, whereby the latter is rotated during mixing operations. To effectually prevent endwise movement of the mixing shell 100 in a rearward direction during dumping operations I provide the rear supporting rollers 102 with truncated conical faces 125 which normally abut and roll upon a bevelled por- 75

tion or face 126 formed integral with or otherwise rigidly secured to the rear annular sprocket wheel 124, substantially in the manner illustrated in Fig. 9. Further, to similarly prevent unseating of the forward end of the shell 100 from its front supporting rollers 102 I provide a roller 127 which is mounted upon the front end of the supplemental frame 103 and is adapted to engage and roll upon the inner surface of the front raceway 101, which in the present instance is of annular formation, and identical in construction to the raceways 19 and 20 hereinbefore described, while the rear raceway 101 in the present instance, is fabricated in the form of a cylindrical throat having a coned outer end 128 provided with a discharge aperture 129 adapted to be closed by a door 130 during mixing operations. To prevent lodgement of the mixed aggregates within the rear end of the shell 100 I provide the latter with an annular outwardly convergent fillet 131, substantially in the manner illustrated in Fig. 9.

An opening 132 for charging the mixing shell 100 with the aggregates is provided in one of the flat sides thereof, said opening being normally closed by a door 133 slidably mounted in guides 134 formed upon said shell.

A water storage tank 135 is laterally disposed and suitably supported upon the forward end of the supplemental frame 103 with its outlet connected to the suction side of a rotary pump 136, which is also mounted upon said frame with its axis in alignment with the axis of the shaft 120. A pipe 137 connected at one end to the discharge of the pump 136 extends upwardly therefrom and at its upper end projects within the mixing shell 100 and is provided thereat with a nozzle 138, said upper end being adapted to pass through the axis of rotation of said shell and in consequence is not affected by the rotative movements of the same. A clutch 139 is provided to interconnect the shaft 120 with the pump 136 to drive the latter whereby the necessary quantity of water is sprayed upon the aggregates during mixing operations.

In operation the herein described transit mixer is placed under a batching chute with the mixing shell 100 in a horizontal disposed position with its charging door 133 open and uppermost and its dumping door 130 closed. Upon charging the shell 100 with the desired quantity of aggregates the door 133 is closed and the water tank 135 filled, following which the transit mixer is started for its point of delivery. Upon nearing such point the operator connects the shaft 109 with the power plant of the truck, to thereby impart rotative movement to the mixing shell 100, through the media of the bevel and sprocket gear mechanism hereinbefore described, which rotative movement also causes end to end wobbling movement of the shell due to its eccentric mounting, the operator then connects the shaft 120 with the pump 136 through the medium of the clutch 139 to spray the necessary quantity of water upon the aggregates. The action produced upon the aggregates by the aforesaid rotative and wobbling movements is identical to that described for the shell 11, and upon the point of delivery being reached and after completion of the mixing operation the supplemental frame 103 and its correlated mixing shell 100 is tilted to the dumping position shown in Fig. 9, whereupon the door

130 is opened and the mixed aggregates dumped out. It is to be here noted that the mode of construction of the transit mixer above described readily permits of the rotation of the mixing shell 100 in a dumping position, or in a position of rest, or in any intermediate position.

In the foregoing description and in the accompanying drawings I have elected to describe and illustrate the mixing shells as being hexagonal in cross-section, but, it is to be understood that such shells may be fabricated with any number of flat sides. It is therefore the primary and principal feature of this invention to provide an eccentrically mounted mixing shell, which is polygonal in cross-section, whereby rotation of such shell will produce a slumping action of the aggregates in a crosswise direction due to the flat sides and the eccentric mounting of the shell will cause the same to wobble and produce a slumping action of the aggregates from the ends of the shell to the center of the same. It will thus be readily apparent and obvious that a thorough intermixture of the aggregates is secured without the aid of baffle plates or any other similar obstructions upon the interior walls of the mixing shell.

While I have herein shown and described the invention with sufficient detail to enable those skilled in the art to which it pertains to understand the mode of construction and the principles involved, it is to be understood that there is no intentional limitation herein to the specific form and precise details of construction shown and described, except as expressly defined by the appended claims, and that various modifications of the same may be resorted to without departing from the spirit of the invention or the benefits derivable therefrom. It is also to be understood that certain features of the invention herein disclosed may be employed in and with other combinations than those shown and described.

What I claim as my invention and desire to secure by Letters Patent is:—

1. In combination with a concrete mixer, of an axially elongated eccentrically mounted voluble mixing shell having closed ends and a polygonal cross-section, one of the sides of said shell forming a door therefor, an auxiliary door on said first mentioned door, and means for rotating the shell.

2. In combination with a motor truck having a driver's cab, a tiltable frame mounted on the truck, a concrete mixer on the tiltable frame, a water tank and piping therefrom to the mixer and a pump interposed in the piping all carried on said tiltable frame, transmission for operating the mixer from the truck power, a shaft operated by the operation of the mixer, and a clutch for connecting said pump to said shaft.

3. In combination with a motor truck having a driver's cab, a tiltable frame mounted on the truck, a concrete mixer on the tiltable frame, a water tank and piping therefrom to the mixer and a pump interposed in the piping all carried on said tiltable frame, transmission for operating the mixer from the truck power, a shaft operated by the operation of the mixer, and a clutch for connecting said pump to said shaft operable from the driver's cab whereby the pump may be engaged with the shaft or disengaged during the transit of the truck.

HUGH P. PARIS.
